Des. 198,283
Patented May 26, 1964

198,283

CLOCK RADIO OR SIMILAR ARTICLE

Raimondo Brenni, La Chaux-de-Fonds, Neuchatel, Switzerland, assignor to Nepro Watch Paolo Spadini, La Chaux-de-Fonds, Neuchatel, Switzerland

Filed Mar. 5, 1963, Ser. No. 73,820

Term of patent 14 years

Claims priority, application Switzerland Jan. 9, 1963

(Cl. D56—4)

Fig. 1

Fig. 2

FIG. 3

FIG. 4

FIG. 1 is a front elevational view of a clock radio, showing my new design;

FIG. 2 is a side elevational view with the side not shown being the same in appearance as the side shown;

FIG. 3 is a front perspective view thereof with the cabinet rotated on the base 90 degrees with respect to the position of FIGS. 1 and 2; and

FIG. 4 is a rear perspective view thereof with the cabinet in the position shown in FIG. 3.

The dominant features of my design reside in the portions shown in full lines.

I claim:

The ornamental design for a clock radio or similar article, as shown and described.
